ABSTRACT: An electrical terminal for use in conjunction with thinly insulated wires and cables is disclosed. The terminal has funnel means therein to guide the conductors of the wires into place in the terminal wire barrels. The terminal has means therein to limit the forward insertion travel of the wire to assure that no wire insulation enters the wire barrel area. The funnel means provides strain relief means in a crimped connection where the wire joins the terminal.

BY Adrian J. Larue

WIRE STOP AND WIRE GUIDE IN TERMINALS AND CONNECTORS

This invention relates to electrical terminals of the type used to connect lead wires to electrical terminals of the type used to connect lead wires to electrical components. More particularly, the invention relates to wire guides and wire stops in electrical terminals for properly locating the lead wires relative to the terminal wire barrels. A terminal according to this invention has means to support the wire where it joins the terminal so as to prevent undue bending stresses on the wire which normally concentrate at that point. This support means is disclosed in U.S. Pat. No. 2,405,111, and comprises a metal sleeve fitted over the terminal barrel.

To illustrate the utility of the present terminal, it may be pointed out that lead wires or cables having an extremely thin insulation cover made of plastic are difficult to terminate in the terminal disclosed in the above-mentioned patent. The thin insulation sometimes permits a prestripped wire to be overinserted into the wire barrel of the terminal. This results in a poorly crimped connection because wire insulation enters the terminal wire barrel. Also, a crimped connection will have little or no strain relief characteristics where the wire joins the terminal. Thinly insulated wires are becoming more useful, particularly in automotive and aircraft applications.

It is therefore an object of this invention to obviate the above undesirable characteristics by providing a tapered ferrule insert means in an insulation support of a terminal.

Another object is the provision of wire stop means to prevent a wire from being overinserted into a wire barrel of a terminal.

A further object is to provide wire guide means to gather wire strands and guide them into a terminal wire barrel.

Still another object is to provide strain relief means to relieve undue bending stresses on a thinly insulated wire where the wire joins a terminal.

Other objects and attainments of the present invention will become apparent to those skilled in the art upon reading of the following detailed description when taken in conjunction with the drawings in which there is shown and described illustrative embodiments of the invention; it is to be understood, however, that these embodiments are not intended to be exhaustive nor limiting of the invention but are given for purposes of illustration in order that others skilled in the art may fully understand the invention and the principles thereof and the manner of applying it in practical use so that they may modify it in various forms, each as may be best suited to the conditions of a particular use.

In the drawings:

FIG. 1 is a perspective view showing tapered ferrules in strip form;

FIG. 2 is a cross-sectional and exploded view of a terminal;

FIG. 3 is a cross-sectional view showing a terminal assembled with a wire in place;

FIG. 4 is a cross-sectional view of FIG. 3 after it has been crimped; and

FIG. 5 is a fragmentary cross-sectional view of an alternate embodiment of FIG. 3.

Referring to FIGS. 2-4, an electrical terminal T according to the present invention comprises a terminal connector section 2 of the apertured-tongue type including a wire barrel section 4 coextensive therewith. Connector section 2 may, of course, take any desirable form. A thin metal insulation support sleeve 6 surrounds and frictionally engages barrel section 4 and extends from the wire entry end of barrel section 4. An insulation sleeve 8 of suitable dielectric material is preferably bonded or secured to support sleeve 6 constituting a preinsulated electrical terminal. The inside surface of barrel section 4 is preferably serrated and the entrance thereto is beveled. The section of sleeve 6 not engaging barrel section 4 is larger in diameter than the section of sleeve 6 engaging barrel section 4 and a margin of the larger diameter section is folded inwardly

into engagement with the inside surface of sleeve 6. A serrated edge 7 is provided along the double thickness area.

Referring to FIGS. 1-3, wire stop and wire guide means may be defined by a conically shaped ferrule or funnel F which is generally made of metal similar to sleeve 6. The large end of funnel F has a flange defined by an out-turned lip 10 which effectively snaps into place behind the serrated edge 7 in sleeve 6. The small end 12 of funnel F has its opening slightly enlarged by thinning the wall thickness, as at 14. Small end 12 is disposed to abut the tapered entrance to barrel section 4 such that a short length of the end 12 enters the barrel section when a funnel is snapped into place in a terminal. This allows a conductor to pass through the small opening and the opening of the wire barrel section without catching or snagging at the opening thereof. End 12 of funnel F in entering wire barrel section 4 when the funnel is assembled into a terminal T provides an arrangement that holds the funnel opening in axial alignment relative to the opening of barrel section 4, and this serves to effectively guide a conductor into wire barrel section 4.

Referring particularly to FIG. 1, a series of funnels 10 are formed from a flat strip 16 of metal by conventional metal-drawing techniques. Funnels 10 remain attached to strips 16 by small connecting straps 18. During automatic assembly of terminals, strips 16 serve to carry funnels 10 to the terminals whereat they are severed from strips 16 and inserted into terminals T.

Referring to FIG. 3, a wire W is stripped of a length of its thin insulation cover CO, and the exposed bare conductor CD is inserted into a terminal T. During entry, the ends of the conductor are gathered and pointed by funnel F. When the conductor CD is fully inserted into barrel section 4, the severed edge E of the insulation cover CO engages the walls of funnel F. This arrangement limits the forward insertion travel of the wire W into the terminal R and properly positions the conductor CD in barrel section 4 so that when it is crimped an effective crimp is attained.

Notice particularly in FIG. 3 that the inside diameter of the small end 12 of funnel F is only slightly larger than the diameter of conductor CD. This arrangement assures that extremely thin insulation on a wire W will not enter wire barrel section 4.

Upon crimping, barrel section 4 is swaged onto conductor CD for a mechanical and electrical connection, as shown in FIG. 4. Simultaneously, a crimp onto the enlarged end of insulation sleeve 8 will swage funnel F, support sleeve 6 and insulation sleeve 8 onto the insulation cover CO of wire W. This arrangement provides strain relief means for thinly insulated wires. Wires with slightly larger insulation covers CO may be used in the present invention, in which cases, the severed edge E of wires W bottom in a larger diameter section of funnel F.

Referring to FIG. 5 wherein terminal Ta which is an alternate embodiment shown, a funnel Fa may be formed from an extension of support sleeve 6. Funnel Fa serves the same purpose as described above. The funnel is integral with an inwardly folded margin of the metallic sleeve 6 and tapers to a single thickness end partially received in the end of the opening of the wire barrel 4. The end of the funnel has an opening which is in axial alignment with the wire barrel opening.

It should be noted that funnel F may be made of plastic or other substantially pliable dielectric material if desired, in which cases, after crimping the funnel will become compressed around the wire insulation CO and provide a connection which is sealed against the ingress of moisture and water.

It should also be noted that solid conductor wire may be used without departing from the scope of the invention.

Connectors, not shown, for joining two wires may utilize the concept taught in the present invention in which case terminal connector section 2 is eliminated, and wire-receiving means and funnel means are incorporated into each end of the connector.

It will therefore, be appreciated that the aforementioned and other desirable objects have been achieved; however, it should be emphasized that the particular embodiments of the

invention, which are shown and described herein, are intended as merely illustrative and not as restrictive of the invention.

The invention is claimed in accordance with the following:

1. In an electrical terminal, the combination comprising: an electrically conductive wire barrel having an opening adapted to receive therethrough a wire conductor of an electrical wire, a metallic sleeve containing said barrel, an insulation sleeve surrounding said metallic sleeve, said metallic sleeve extending beyond an end of said barrel and having an inwardly folded margin portion in spaced relationship from said wire barrel and, said margin portion generally of annular configuration and in engagement with the inside of said metallic sleeve, and a freely insertable funnel of resilient material inserted within and past said annular margin and into the inside of said metallic sleeve, said funnel being retained within said sleeve and in engagement against an edge of said inwardly folded margin and the end of said wire barrel.

2. The structure as recited in claim 1, wherein said funnel tapers to a thin wall portion defining an opening, said thin wall portion engaged against said wire barrel end, and said thin wall opening and said wire barrel opening being axially aligned.

3. The structure as recited in claim 2, wherein, said funnel is of resilient material and a large end of said funnel has an outer lip which is initially resiliently compressible upon said insertion past said inwardly folded margin portion and sub-

sequently resiliently expandable and in engagement against the edge of said margin portion, said funnel being located between and in engagement against said margin portion edge and said wire barrel end.

5. The structure as recited in claim 3, wherein, said funnel is of resilient material and includes a large end with an outer lip which is initially resiliently compressible upon insertion of the funnel past said inwardly folded margin, said lip additionally being resiliently expandable and in engagement against the edge of said inwardly folded margin, with said funnel located between and in engagement against said margin edge and said wire barrel end.

6. The structure as recited in claim 1, wherein, said funnel is partially received in said wire barrel opening.

7. The structure as recited in claim 2, wherein, said thin wall of said funnel is partially received in said wire barrel opening.

8. The structure as recited in claim 1 and further including: an electrical wire having a wire conductor end portion protruding from an insulation layer, which wire conductor end portion is inserted interiorly of said wire barrel with a portion of the insulation layer being received interiorly of said funnel and the metallic sleeve, said wire barrel being crimped in mechanical and electrical engagement on said wire conductor end portion, and said metallic sleeve and said funnel being crimped simultaneously over said insulation layer with said funnel in crimped engagement with said insulation layer.
